(No Model.)

W. KRAUS.

RAISED LETTERS FOR SIGNS.

No. 247,200.

Patented Sept. 20, 1881.

UNITED STATES PATENT OFFICE.

WILHELM KRAUS, OF NEW YORK, N. Y.

RAISED LETTERS FOR SIGNS.

SPECIFICATION forming part of Letters Patent No. 247,200, dated September 20, 1881.

Application filed July 25, 1881. (No model.)

To all whom it may concern:

Be it known that I, WILHELM KRAUS, of the city of New York, county and State of New York, have invented a new and useful Improvement in Raised Letters for Signs, of which the following is a specification.

In the accompanying drawings, Figure 1 is a face view of a letter made according to my improvement. Fig. 2 is a back view of the same. Fig. 3 is a longitudinal section on the line xx , Fig. 2; Fig. 4, a similar section, on an enlarged scale, on the line yy , Fig. 2; and Fig. 5, a central longitudinal section of a modification of my invention.

Similar letters of reference indicate corresponding parts in all the figures.

This invention relates to an improvement in the construction of raised letters, which are of a beautiful appearance and very durable, and are to be used for signs or similar purposes.

The invention consists in the construction of a raised letter for signs composed of a metallic frame which forms the outline of the letter and leaves one or more open spaces within its face, and of one or more panes of glass or equivalent material, which are fastened against the back of said frame so as to close said open spaces, all as hereinafter more fully pointed out.

The invention also consists of the details of construction hereinafter specified.

In the drawings, the letter A represents one of my improved raised letters.

I have shown the letter T, but of course all the other letters may be constructed according to the same principle. It is provided with pins a , by which it may be attached to a sign-board or other support, and is composed of a metallic frame, b , which forms the outline of the letter and leaves one or more open spaces in its face. These spaces are closed by one or more panes, d , which are fastened against the back of the frame b in such a manner as not to interfere with the direct attachment of said frame to the sign-board. In the drawings I

have shown the letter to be made with inclined 45 sides; but it may also be made with upright sides, in which case the open spaces are formed in the front face of the letter parallel to the sign-board.

Each of the panes d is placed against the 50 back of the frame b in such a manner that the frame overlaps the edges of the pane. The glass is gilt or plated at its back, if desired, as shown at e , so that the plated side is not exposed, and is backed by a piece of pasteboard, 55 f , or equivalent material. The glass and backing are held in place by metallic lugs g , fastened to the frame b and extending over their edges. The letter thus formed is durable and very ornamental.

In the modification shown in Fig. 5 a transparent or translucent material—such as glass not plated, stained glass, or porcelain—is applied within the open spaces of the frame b without any backing. A portion of the sign-board B is, moreover, cut away behind the letter. In this way the letter will appear illuminated when lights are placed behind the sign-board.

I claim as my invention—

1. As a new article of manufacture, a raised letter, A, for signs composed of a metallic frame, b , which forms the outline of the letter and leaves one or more open spaces in its face, and of one or more panes of glass, d , or equivalent material, which are fastened against the back of the frame b , so as to close said open spaces, substantially as herein shown and described.

2. The raised letter A, composed of the metallic frame b , panes d , having gilt back e , and of the backing f and fastening-lugs g , substantially as specified.

WILHELM KRAUS.

Witnesses:

RUDOELF KRAUS,
FRANK V. BRIESEN.
